WINDING MACHINE.

APPLICATION FILED NOV. 2, 1904.

2 SHEETS—SHEET 1.

The drawing shows a mechanical assembly with the following labeled parts:

- m : A vertical component on the left.
- t : A small component near the top center.
- e : A component on the left side.
- l : A component on the left side.
- g : A component on the left side.
- p : A component on the left side.
- e_1 : A component on the left side.
- f : A component on the left side.
- l' : A component on the left side.
- a : A component on the right side.
- a' : A component on the right side.
- d : A component on the right side.
- g_1 : A component on the right side.
- a_1 : A component on the right side.
- g_2 : A component on the right side.
- d' : A component on the right side.
- g_3 : A component on the right side.
- a_2 : A component on the right side.

UNITED STATES PATENT OFFICE.

JAMES EDWARD BROADBENT AND JOSEPH BROADBENT, OF STALEYBRIDGE, ENGLAND, ASSIGNORS TO ROBERT BROADBENT & SON LIMITED, OF STALEYBRIDGE, ENGLAND.

WINDING-MACHINE.

No. 855,930.

Specification of Letters Patent.

Patented June 4, 1907.

Application filed November 2, 1904. Serial No. 281,134.

To all whom it may concern:

Be it known that we, JAMES EDWARD BROADBENT and JOSEPH BROADBENT, subjects of the King of Great Britain and Ireland, and both residing at Phoenix Iron Works, Staleybridge, in the county of Chester, England, have invented new and useful Improvements in or Applicable to Winding-Machines, of which the following is a specification.

10 This invention relates to improvements in or applicable to winding machines, with the object of simplifying the mechanism for winding either conical or parallel bobbins, but said mechanism is alike applicable to machines employed in other kinds of winding.

In the accompanying drawings to which we hereinafter refer, Figure 1 is a front view, Fig. 2 a plan and Fig. 3 a transverse vertical section on line A—A, of Fig. 2, of a winding machine in which our invention is incorporated.

In these drawings the same letters refer to like parts.

According to and for the purpose of our said invention we mount in a frame as *a* two screws *b* and *c* at a little distance apart and parallel to each other which are formed preferably with square threads. Said screws may be either both right or both left hand. 25 A tooth wheel is fitted on one and the same end of each screw, said tooth wheels *d* and *d'* gearing into each other so that the screws are rotated in reverse directions. We fit on a rod *e* placed centrally between but above and parallel with said screws a rocking bar *f* extending at a right angle on each side of the rod over the screws hereinbefore named, and secure to the under side of and near to each end of said bar a projection immediately 35 above the axis of each screw arranged so that the projection *j* may fit between the threads of the screw *b*, and the projection *j'* may fit between the threads of the screw *c* the aforesaid rocking bar being so arranged that when 40 one projection is engaging with a screw the other is disengaged. A nut segment having threads corresponding to the threads of the screws might be used instead of the bowls.

At the outside of each screw a short flat 50 topped angular bar as *g* is fixed, the length

of said bars being regulated according to the length of the bobbin to be wound; a small flat or beveled finger *f'* is formed or fitted on each end of the aforesaid rocking bar *f*, one of said fingers sliding under the flange 55 forming the top of one of the side angular bars, when the rocking bar is moved along by one of the projections engaging one of the screws on the same side, and the other finger sliding on the top of the other angular bar. At a little distance from one end of each of the aforesaid angular bars but in opposite positions small inclined planes *l* *l'* are fitted, and at the opposite end of each of these bars a compression spring *p* is fitted 60 also in opposite positions. Motion is transmitted to a pulley as *q* fitted on the end of one of the aforesaid screws on which the tooth wheels are fitted as hereinbefore described which causes the screws to rotate in 65 opposite directions: One of the projections that is fixed under the rocking bar is caused to engage with one of the screws by the flat finger on the same end of the rocking bar being pressed down at the commencement 70 of the stroke by one of the aforesaid springs, so as to come under the flange of the angular side bar *g*, and when at the end of the stroke it is released from said flange it mounts one of the small inclines *l* or *l'* and causes the 75 other flat finger to be depressed and the other projection to engage in the opposite screw thereby reversing the traverse of the guide *m* that is fixed on an extension of the rod on which the rocking bar is fitted, the 80 first named finger sliding back on the top of the flange of the side bar.

Various modifications of our invention by which other means are employed to raise the projections may be made without 85 departing from the breadth of our conception.

The mechanism hereinbefore described may be placed or fitted in a box containing oil which is fixed to the frame of the machine, 90 one or more being employed according to the length of the machine.

We are aware that it has been proposed to use in apparatus for winding bobbins or spools two right or two left hand screws, ro- 95

tating in opposite directions for the purpose of causing to reciprocate a carriage provided with a rocking lever carrying nut segments to engage with the screws and we do not claim such an arrangement broadly, but

We declare that what we claim is:

In combination with two parallel right or left hand screws rotating in opposite directions, a rocking bar provided with means at its ends to engage the screw threads, two angular side bars adapted to keep one end

of said rocking bar engaged with a screw and means for rocking the bar.

In testimony whereof we have signed our names to this specification, in the presence 15 of two subscribing witnesses.

JAMES EDWARD BROADBENT.
JOSEPH BROADBENT.
